EXERCISER

Harry C. Weaver, San Gabriel, Calif., assignor, by direct and mesne assignments, to William E. Sharp, Chicago, Ill.; Minnie E. Sharp executrix of the estate of said Sharp, deceased

Application August 27, 1928, Serial No. 302,177

11 Claims. (Cl. 128—63)

My invention relates to exercising machines and more particularly to a machine for vibrating an engaging member or belt adapted to surround a portion of the anatomy of an individual.

5 It is desirable in such a machine to impart to the engaging member or belt a reciprocating motion through a short distance.

It is an object of my invention to provide a machine which will impart to an engaging member 10 adapted to contact a portion of the anatomy of an individual reciprocating motion through a short distance.

Because of the great tension exercised on the engaging member or belt it is necessary to provide 15 an actuating mechanism which is extremely rugged in construction.

It is another object of my invention to provide 20 a machine of the class described providing a mechanism capable of efficient and long continuing operation with great tension exerted upon the engaging member or belt.

It is still another object of my invention to provide 25 a machine of the class described in which the mechanism is very simple and the parts very few in number.

Further objects and advantages will be made 30 evident in the following description and the accompanying drawing, in which:

Figure 1 illustrates a vertical sectional view 35 of one embodiment of my invention.

Figure 2 illustrates a perspective view of the upper portion of the embodiment shown in Figure 1.

Figure 3 is a horizontal sectional view on the 35 line 3—3 of Figure 1, looking in the direction of the arrows, the vibrating bar thereabove being illustrated in dot-dash lines.

Referring to the drawing and particularly to Fig. 1, the numeral 11 represents a mechanism 40 support and housing comprising a lower portion 12, shown approximately cubical merely for the sake of illustration, and an upper portion 13 communicating with the lower portion 12, the upper portion 13 being substantially frusto-conical. Received in the top of the upper portion 13 of the housing 11 is a bushing 14 comprising a cylindrical portion 15 extending downwardly in the upper portion 13 of the housing 11, and a flange portion 16. As best 45 shown in Fig. 1, the flange portion 16 of the bushing 14 has a diameter substantially equal to the diameter of the upper end of the upper portion 13 of the housing 11.

Adapted to be journaled in the bushing 14 is a 50 preferably vertical shaft or rod 17 to the upper

end of which is secured, as by a pin 18, an approximately semi-spherical cap 19 of a diameter substantially equal to the diameter of the flange portion 16 of the bushing 14 and the upper end of the upper portion 13 of the housing 11. The 5 lower surface 20 of the cap 19 is adapted to bear upon the flange portion 16 of the bushing 14. Connected to the cap 19 are two oppositely extending horizontal arms 21. As best shown in Fig. 2, the arms 21 may be circular in cross-section except for a flat side 22.

The normally vertical rod 17 extends downwardly centrally through the upper portion 13 into the lower portion 12 of the housing 11 and is journaled near its lower end in a bushing 23 supported in an inwardly projecting portion 24 of the housing 11. Non-rotatably attached to the vertical rod 17 below the bushing 23, as by a pin 25, is a horizontal connecting arm or crank 26. Rotatably attached to the other end of the arm 20 26 as by a crank-pin 27 is a connecting rod or link 28, the other end of which is rotatably attached as by a crank pin or pivot 29 to a crank 30. As best shown in Fig. 1, the crank 30 is non-rotatably attached to a shaft 31 of a motor 32 and is 25 associated with a counterbalance 33 on the opposite side of the shaft 31, the motor 32 being so positioned that its shaft 31 and its axis of rotation are parallel to the rod 17, that is, normally vertical. Attached to the casing of the motor 32 are 30 arms 34, which are secured as by bolts 35 to the inner surface of the lower portion 12 of the housing 11.

The housing 11 may be attached as by bolts 36 passing through flanges 37 extending inwardly 35 from its lower portion 12 to one end of a base 38, whose other end extends beyond the housing 11, as best shown in Fig. 1. Openings 39 with covers 40 may be provided in the top and side of the lower portion 12 of the housing 11 to permit the supplying of lubricant to the motor 32 and grease cups associated with the crank-pin 27 and the link 28.

Adapted to be slidably mounted upon the arms 21 at the top of the vertical rod 17 is a pair of 45 hooks 42 with hubs having a non-circular bore 43 corresponding with the non-circular section of the arms 21 but slightly larger to provide the necessary clearance. Each hook 42 is provided with a thumb-screw 44 preferably adapted to 50 pass through that portion of the hub of the hook 42 adjacent to the flat side of the cylindrical bore 43 and to bear against the flat portion 22 of the arms 21 to secure each of the hooks 42 in any desired position upon the arms 21 in order to regu- 55

late the amplitude of vibration or reciprocation imparted to the associated belt 47. Each of the hooks 42 is adapted to receive a ring 45 linked to an eye 46 secured to each end of an engaging member, applicator or massaging belt 47, as best shown in Fig. 2.

The operation of the described embodiment of my invention is as follows:

When the motor 32 is energized, the shaft 31 and the associated crank 30 are caused to rotate. As the crank 30 rotates, the pivot 29 and that end of the link 28 connected thereto rotate about the axis of the shaft 31 and the other end of the link 28 together with the pin 27 and one end of the arm 26 associated therewith are thereby caused to move back and forth through an arc about the axis of the vertical rod 17 for each revolution of the crank 30. The oscillating motion of the arm 26 is imparted to the vertical rod 17 and from the vertical rod 17 to the arms 21 associated therewith. As the arms 21 swing back and forth about the axis of the vertical rod 17 an adjustable reciprocating motion of high frequency is imparted to the engaging member or belt 47 so that when the engaging member 47 is caused to contact a portion of the anatomy of an individual standing upon the base 33 a vibratory motion of high frequency is imparted to the flesh of the individual resulting in increased circulation, with consequent well known beneficial effects.

It is evident that I have provided an exercising machine capable of imparting reciprocating motion through a short distance to an engaging member adapted to contact a portion of the anatomy of an individual. Moreover, since the counterbalance 33 may be so designed as to counterbalance the link 28, it is likewise apparent that I have provided a mechanism of the class described capable of efficient and long continued operation even with great tension exerted upon the engaging member 47. It is also seen that by positioning the motor 32 with its shaft 31 in a vertical position and by providing a very compact mechanism comprising the crank 30, the link 28, the arm 26 and the vertical rod 17, I have provided a machine of the class described embodying a mechanism which is extremely simple and which comprises but very few parts.

Although the form of embodiment of my invention herein illustrated and described is fully capable of fulfilling all of the objects primarily stated, I do not wish to be restricted to this form, for my invention is capable of various other embodiments all coming within the scope of the claims which follow.

I claim as my invention:

1. In an exercising machine, the combination of: an engaging member adapted to contact a portion of the anatomy of a person; a rod providing arms, said arms being adapted to be associated with said engaging member; a connecting arm non-rotatably attached to said rod; a shaft adapted for rotating, the axis of said shaft being substantially parallel to the axis of said rod; a link, one end of which is rotatably attached to said connecting arm and the other end of which is associated with said shaft eccentric to the axis of rotation of said shaft; means associated with said shaft for counterbalancing purposes, and means for rotating said shaft for moving said link and imparting oscillating motion to said connecting arm, said rod and said engaging member.

2. In an exercising machine, the combination of: an engaging member adapted to contact a

portion of the anatomy of a person; a rod providing arms, said arms being adapted to be associated with said engaging member; a connecting arm non-rotatably attached to said rod; a shaft adapted for rotating, the axis of said shaft being substantially parallel to the axis of said rod; a link, one end of which is rotatably attached to said connecting arm and the other end of which is associated with said shaft eccentric to the axis of rotation of said shaft; means associated with said shaft for counterbalancing purposes, and means for rotating said shaft for moving said link and imparting oscillating motion to said connecting arm, rod and engaging member and a housing adapted to surround said last named means, said counterbalancing means, said link, and said connecting arm and to surround and journal a portion of said rod.

3. In a vibrating machine, the combination of: an engaging member adapted to contact a portion of the anatomy of a person; a rod providing arms, said arms being adapted to be associated with said engaging member; a connecting arm non-rotatably attached to said rod, said connecting arm being disposed substantially at right angles to said rod; a shaft adapted to be rotated, the axis of said shaft being substantially parallel to the axis of said rod; a link, one end of which is rotatably attached to said connecting arm, and the other end of which is rotatably associated with said shaft eccentric to the axis of rotation of said shaft; means associated with said shaft for counterbalancing purposes; and means for rotating said shaft.

4. In a vibrating machine, the combination of: an engaging member adapted to contact a portion of the anatomy of a person; a rod providing arms, said arms being adapted to be associated with said engaging member; a connecting arm non-rotatably attached to said rod, said connecting arm being substantially at right angles to said rod; a motor so positioned that its driving shaft is substantially parallel to said rod; a link, one end of which is rotatably attached to said connecting arm, and the other end of which is rotatably associated with said shaft eccentric to the axis of rotation of said shaft, and means associated with said shaft for counterbalancing purposes.

5. In a vibrating machine, the combination of: an engaging member adapted to contact a portion of the anatomy of a person; a rod providing arms, said arms being adapted to be associated with said engaging member; a connecting arm non-rotatably attached to said rod, said connecting arm being substantially at right angles to said rod; a motor so positioned that its driving shaft is substantially parallel to said rod; a link, one end of which is rotatably attached to said connecting arm, and the other end of which is rotatably associated with said shaft eccentric to the axis of rotation of said shaft; means associated with said shaft for counterbalancing purposes; and a housing adapted to surround said counterbalancing means, said link and said connecting arm, and to surround and support said motor and said rod.

6. In an exercising machine, the combination of: a vertical rod having a pair of horizontal arms at its top; an engaging member adapted to contact a portion of the anatomy of a person; hooks slidably adjustable upon said arms, said hooks being adapted to receive the ends of said engaging member; a horizontal arm non-rotatably attached to the lower end of said vertical rod; a motor positioned with its axis of rotation and shaft vertical; a crank non-rotatably associated with said

- shaft of said motor; and a horizontal link, one end of which is rotatably pivoted to said arm, and the other end of which is rotatably pivoted to said crank.
5. 7. In an exercising machine, the combination of: a vertical rod having a pair of horizontal arms at its top; an engaging member adapted to contact a portion of the anatomy of a person; hooks slidably adjustable upon said arms, said hooks being adapted to receive the ends of said engaging member; a horizontal connecting arm non-rotatably attached to the lower end of said vertical rod; a motor positioned with its axis of rotation and shaft vertical; a crank non-rotatably associated with said shaft of said motor; a horizontal link, one end of which is rotatably pivoted to said connecting arm, and the other end of which is rotatably pivoted to said crank; and a housing adapted to surround said horizontal link, said horizontal connecting arm and said crank, to surround and journal said vertical rod and to surround and support said motor.
8. In an exercising machine, the combination of: a vertical rod having a pair of horizontal arms at its top; an engaging member adapted to contact a portion of the anatomy of a person, the ends of said engaging member being slidably adjustable upon said arms; a horizontal connecting arm non-rotatably attached to the lower end of said vertical rod; a motor positioned with its axis of rotation and shaft vertical; a crank non-rotatably associated with said shaft of said motor; a horizontal link, one end of which is rotatably pivoted to said connecting arm, and the other end of which is rotatably pivoted to said crank; and a housing adapted to surround said horizontal link, said horizontal connecting arm, and said crank, to surround and journal said vertical rod and to surround and support said motor.
40. 9. An exercising machine comprising a member adapted to contact a portion of the anatomy of a person, an upright rod adapted to oscillate about its axis, arms extending from said rod and operatively rigid therewith, means normally connecting said first-mentioned member to said arms, an operating arm non-rotatably connected to said rod, an upright shaft mounted for rotation about its axis and disposed substantially parallel to said rod, an operatively rigid link, upright pivot means connecting one end of said link to said operating arm and the other end of said link to said shaft eccentric to the axis of rotation thereof, and means for rotating said shaft to move said link and impart oscillating motion to said arm, rod and first-mentioned member.
10. An exercising machine comprising a base, a housing with walls upstanding from said base, a motor having a shaft and provided with a base connected to one of said housing walls so that its shaft normally extends vertically, a bearing carried by said housing, a normally vertical rod journaled in said bearing, means carried by the lower portion of said rod for actuation from the shaft of said motor, a rocker arm pivotally mounted on said housing for actuation by said vertical rod, an applicator with ends normally connected to said rocker arm, each independently slidable therealong and adapted to be actuated thereby, and means holding each end of said applicator on said arm in individually adjusted position.
11. An apparatus for kinesitherapy treatment, including an electric motor, a mount therefor upon which the motor is carried in elevated position with its armature shaft vertically disposed, an oscillatory yoke mounted upon the motor housing for oscillatory motion about a vertical axis, the arms of said yoke extending laterally beyond opposite sides of the motor for connection with an applicator and an operative connection between the armature shaft and the yoke.

HARRY C. WEAVER.
